UNITED STATES PATENT OFFICE.

FREDERICK W. SCHAEFFER, OF CHICAGO, ILLINOIS.

FIREPROOF WINDOW FRAME AND SASH.

No. 819,810.

Specification of Letters Patent.

Patented May 8, 1906.

Application filed February 25, 1905. Serial No. 247,391.

To all whom it may concern:

Be it known that I, FREDERICK W. SCHAEFFER, a citizen of the United States, residing at Chicago, in the county of Cook and State 5 of Illinois, have invented a new and useful Improvement in Fireproof Window Frames and Sash, of which the following is a specification.

This invention relates to a window frame 10 and sash; and the object of the invention is a frame and sash which shall be fireproof, not only as to materials, but in construction, thereby preventing the entrance of fire into a building by way of the windows.

15 The invention consists of the novel features of construction and combination of parts hereinafter described, pointed out in the claims, and shown in the accompanying drawings, in which—

20 Figure 1 is a perspective view of the window. Fig. 2 is a horizontal section taken through the frame and upper sash. Fig. 3 is a vertical section through the longitudinal center of the window.

25 In the drawings, A represents a metal window-frame, preferably formed of sheet metal and having a false bottom A', arranged some distance above the true bottom A², as shown in Fig. 3. At the sides the side 30 members of the frame A are angled rearwardly—that is, away from the sash—forming a compartment in which work the counterweights B², which are supported by the cables B', running over sheaves B. The window-sash is formed at the top and sides of a channel-iron C, having an inwardly-extending flange C', and upon the channel-iron or beam C is bolted or riveted an angle-iron D, having one member parallel with the flange 35 C' of that particular channel-beam, and a groove is thus formed between the flanges C' and the angle-iron D in each sash. A piece of sheet-iron is secured to the underface of the angle-bar D of each sash, as shown at E, and is 40 carried over the channel-beam and brought around to the flange C', and in the case of the lower sash a portion of the metal sheet E projects horizontally in the plane of the upper edge of the beam C and is bent back upon itself, as at E', thus forming a weather-strip.

The lower horizontal member of the upper sash is formed of a channel-beam G, having the upwardly-extending flange G' and carrying an angle-iron H, arranged parallel to the flange G'. A piece of sheet metal E² is secured to the inner face of the angle-iron H

and projects horizontally beyond same and is then bent back upon itself, as shown at E³, and is then carried around the beam G. By means of this construction air-spaces are 60 formed extending around the sash.

The lower horizontal member of the lower sash is formed of the channel-beam J and the parallel angled irons J', a metal sheeting E⁴ being arranged between the angle-irons and 65 the channel-beams. The glass K fits in the grooves formed by means of the various channel-beam flanges C' and G' and the angle-irons D, H, and J' and is packed with asbestos, rubber, putty, or similar material K'. 70

The false bottom A' is supported or braced by a beam L, and in the space between the two bottoms A' and A² is arranged a trough L', communicating at its lower end with an outwardly and downwardly inclined chute 75 L², which discharges condensations of moisture. The frame A is braced at the sides by the brackets or brace-rods A³, and in the recesses of the frame A in which run the sashes are arranged channel-beams M, in which the 80 side channel-beams C slide. It will be noticed that the various parts overlap and that a practically fireproof joint is formed when the sashes are in closed positions.

Having thus fully described my invention, 85 what I claim as new, and desire to secure by Letters Patent, is—

1. The combination with a sheet-metal window-frame recessed to hold the side members of a sash, of channel-beams arranged in said recesses, and a sash having its sides formed of channel-beams, the said beams being adapted to slide within the channel-beams of the frame. 90

2. The combination with a sheet-metal window-frame, of upper and lower sashes formed of channel-beams, said beams having an inwardly-extending flange, angle-irons carried by the beams parallel to the said flanges, glass panes held between the flanges 100 and the angle-irons, and metal sheeting partially inclosing the channel-beams. 95

3. The combination with a sheet-metal window-frame, channel-beams carried by the frame, a sash comprising side members of channel-beams adapted to rest within and slide in the first-mentioned channel-beams, an upper sash member comprising a channel-beam having an inwardly and downwardly extending flange, and angle-iron parallel to 105 the flange, metal sheeting inclosing the channel-beam and forming an air-space, a lower 110

side member comprising a channel-beam, parallel angle-irons carried thereby, metal sheeting arranged between the angle-irons and the said lower channel-beam and partially inclosing the same, and a pane held between the flange and the angle-iron at the top of the sash and between the angle-irons

at the bottom of the sash, as and for the purpose set forth.

FREDERICK W. SCHAEFFER.
